UNITED STATES PATENT OFFICE

96,718

DESIGN FOR A WREATH

Leo Alter, Chicago, Ill.

Application October 18, 1934, Serial No. 53,676

Term of patent 3½ years

To all whom it may concern:

Be it known that I, Leo Alter, a citizen of the United States, residing at Chicago, in the county of Cook and State of Illinois, have invented a new, original, and ornamental Design for a Wreath, of which the following is a specification, reference being had to the accompanying drawing, forming part thereof.

Figure 1 of the drawing is a perspective view of a wreath showing my new design; and Fig. 2 is a

radial section, taken approximately on line 2—2 of Fig. 1.

The wreath is convex on the front side and is flat on the back; and the front side is covered with strings of beads arranged roughly in the form of circles concentric with the wreath.

I claim:

The ornamental design for a wreath, as shown and described.

LEO ALTER.
